LOOSE LEAF BINDER

Paul O. Unger, Glen Ellyn, Ill., assignor to Wilson-Jones Company, Chicago, Ill., a corporation of Massachusetts

Application May 26, 1932, Serial No. 613,607

10 Claims. (Cl. 129—24)

This invention relates to a loose leaf binder and more particularly to mechanism for locking the binder in its closed position.

It is well known that loose leaf binders are widely used to hold court records and other vital statistics. It has been a problem to provide adequate means to prevent tampering with such records because of the ease with which sheets may be removed from or inserted in most loose leaf binders. Many States require that loose leaf binders containing records be provided with locks and keys. However, even this safeguard does not insure safety because a person lawfully using a record book may leave the same unlocked and return the key to its custodian.

It is an object of this invention to provide means to prevent the loose leaf binder from being opened for the insertion or removal of sheets by unauthorized persons. It is a further object of this invention to provide means making it impossible for a person lawfully using a record book to leave the same unlocked without the knowledge of the custodian of the records. It is a further object of this invention to provide means whereby the binder may be permanently locked. Other objects of this invention will become apparent upon reading the following specification taken in conjunction with the accompanying drawing in which:

Figure 1 is a perspective view of a loose leaf binder embodying a preferred form of the invention;

Figure 2 is a section taken through the center of the back of the binder with parts broken away to facilitate the illustration;

Figure 3 is a fragmentary detail perspective of the temporary lock in unlocked position.

Figure 4 is a view similar to Figure 3 showing the lock in locked position.

Figure 5 is a transverse section of the lock.

In the drawing the reference numerals 2 and 3 indicate a pair of cover sections connected to a back section 4 by means of hinges 5. The back section 4 includes a trough-shaped metal plate 6 having a cover 7 of leather, fibre board or similar material on its outer face. A pair of metal sheaths 8 are welded to the metal plate 6 at its edges. The sheaths 8 are recessed, as indicated at 9, so as to receive the ends of a plurality of posts 10 upon which a plurality of loose leaves 11 may be impaled. A pintle slide 12 is mounted in each sheath 8. The pintle slide is recessed, as indicated at 13, to provide prongs 14 which are adapted to engage with openings 15 in the ends

Each pintle slide is provided with a notch 16 in its lower edge. A piece of spring wire 17 is welded to the metal plate 6 so that its free end 18 presses against the lower surface of the pintle slide adjacent the notch 16. A lug 19 is secured to one end of the pintle slide by means of a screw 20. The lug 19 abuts the end of the sheath 8 in the normal travel of the pintle slide just short of the point where the free end of the spring 18 would snap into the notch 16. A metal shield 21 welded to the sheath 8 and the plate 6 serves to conceal the spring 17 and to prevent tampering with the permanent lock. It is obvious that the shield 21 may be made integral with the sheath 8 if desired.

When it is desired to lock the binder permanently so that no leaves can be inserted or removed, the lug 19 is removed from the end of the pintle slide and the slide is pushed into the sheath far enough to allow the free end of the spring to snap into the notch 16. The pintle slide can not be forced through the opposite end of the sheath because that end is closed.

A key-operated lock 22 adapted to lock the binder temporarily before permanent locking is desired is positioned within the trough of the back portion 4. One end of the back section is provided with a flange 23 having an opening 24 through which a key 25 may be inserted to operate the lock mechanism. This structure is of particular advantage in that the beauty of the binder is not lessened by any unsightly openings or projections. The top of the lock 22 does not project beyond the top of the flange 23. This structure has the further advantage that it makes it possible for a single lock to lock both pintle slides simultaneously.

The lock 22 includes a metal casing 26 shaped to fit the contour of the trough of the back section 4 and welded thereto. The casing is provided with a plurality of lugs 27 which fit in slots in the cover member 28 and are bent over to retain the cover member in position. The metal casing and its cover are left open at the end positioned adjacent the flange 23 of the back section to allow access to the working parts of the lock by the key 25. A metal guide member 29 having upturned flanges parallel to the walls of the casing 26 is welded to the casing. The side walls of the casing 26 are notched, as indicated at 30 and 31, to guide and support a pair of transversely slid able arms 32 and 33. The upturned flanges of the guide member 29 are similarly notched.

The arm 32 is provided with a pair of upstand-

ing lugs 34 and 35 adapted to be operated by the cam surfaces 36 and 37, respectively, positioned on opposite sides of one prong of the key 25. The arm 33 is provided with a pair of depending lugs 38 and 39 adapted to be operated by the cam surfaces 40 and 41 respectively, positioned on opposite sides of the other prong of the key 25. The arm 32 is bent upwardly at its outer end as indicated at 42. The arm 33 is provided with a 10 similar upturned portion 43. These upturned portions 42 and 43 are adapted to be moved adjacent the pintle slides 12 slidably mounted along opposite sides of the back section 4 of the binder. Each pintle slide 12 is provided with an integral 15 lug 44 so positioned that when the pintle slide is in closed position the upstanding portion of one of the arms 32 or 33 may be moved adjacent the pintle slide in front of the lug 44 and thus prevent movement of the pintle slide to open position until the arm is first moved out of the path 20 of travel of the lug 44.

The arms 32 and 33 are each notched, as indicated at 45, to receive a detent 46 when the arms are in extended, or locking, position. The 25 detent 46 prevents accidental movement of the arms 32 and 33. The detent 46 is provided with a spring housing 47 in which a U-shaped member having springs 48 encircling its arms 49 is positioned. The arms 49 extend through small 30 openings 50 so as to retain the springs 48 between the rear wall of the casing 26 and the front wall of the spring housing 47. The springs exert continuous force against the detent 46 so that whenever the arms 32 and 33 are in extended position 35 the detent snaps in place in the notches 45.

The casing 26 is provided with an upstanding lug 51. The lug 51 may be welded to the guide member 29 as shown, or may be merely struck out of the guide member and bent upwardly. The 40 key 25 is provided with an aperture 52 adapted to fit over the lug 51 when the key is in its innermost position. This serves to hold the key in place and prevents the spring-pressed member 47 from forcing the key outwardly.

45 The operation of the temporary lock 22 is as follows:

Starting with a closed book, the elements of the lock are in the positions indicated in Figure 4 of the drawing. A key 25 inserted through the 50 opening 24 in the flange of the back section of the book will have its prongs automatically positioned by the upstanding flanges of the guide member 29 so that one prong moves between the lugs 34 and 35 and the other prong moves between the lugs 38 and 39. The prongs then engage the 55 front wall of the spring housing 47 and force it back against the pressure of the springs 48, thus moving the detent 46 out of the notches 45. Further inward movement of the key brings the cam 60 surface 37 into engagement with the lug 35 and the cam surface 41 into engagement with the lug 39. These cam surfaces force the lugs inwardly and since the lugs 35 and 39 are rigidly attached to the arms 32 and 33, respectively, the 65 arms 32 and 33 are moved inwardly so that the upwardly extending portions 42 and 43 are moved out of the path of the travel of the lugs 44 on the pintle slides 12. When the key has reached its innermost position it is snapped down over 70 the lug 51 so that the key will remain in position and the operator may have both hands free. This position of the lock elements is illustrated in Figure 3.

75 After the leaves are inserted or removed, the key is lifted off the lug 51 and pulled outwardly.

If either pintle slide 12 is in open position, the lug 44 prevents outward movement of the vertical portion 42 or 43 of the arm 32 or 33, respectively. If either arm can not move outwardly, the lug 34 or 38 will bind against the cam surface 36 or 40, respectively, and will prevent withdrawal of the key 25. If both pintle slides are in closed position, outward movement of the key 25 causes the cam surfaces 36 and 40 to engage the lugs 34 and 38, respectively, and move the arms 32 and 33 outwardly to locking position. The spring-pressed detent 46 follows the key and snaps into position in the notches 45 to hold the arms 32 and 33 in locking position as soon as the notches are in alignment therewith.

80 Although I have specifically described a single embodiment of my invention it is obvious that many details may be changed or modified without departing from the spirit or scope of my invention. Accordingly, I do not desire to be restricted to the exact details disclosed except as 85 limited by the appended claims.

90 I claim as my invention:

1. In a loose leaf binder, a pintle slide, and a 95 key-operated temporary locking mechanism, said temporary locking mechanism including means to prevent withdrawal of its key while said slide is in unlocked condition.

2. In a loose leaf binder, a pair of pintle slides operable independently of each other, and a single 105 key-operated locking mechanism operatively connected to said slides, said locking mechanism including means to prevent withdrawal of its key while either of said slides is in unlocked condition.

3. In a loose leaf binder, a pair of pintle slides, and a single key-operated temporary locking mechanism operatively connected to both of said slides, said temporary locking mechanism including means to prevent withdrawal of its key while 115 either of said slides is in unlocked condition.

4. In a loose leaf binder, a pair of cover sections connected by a trough-shaped back section, and a key-operated locking mechanism contained within the trough of said back section, said locking mechanism including means to prevent withdrawal of its key while in unlocked condition.

5. In a loose leaf binder, a back section, a pintle slide movable longitudinally along said back section, a lug on said slide near one extremity 125 thereof, a bar movable transversely into and out of the path of travel of said lug, means to actuate said bar, and means on said bar to prevent withdrawal of said actuating means while said bar is positioned out of the path of travel of said lug.

6. In a loose leaf binder, a back section, a pair of pintle slides movable longitudinally along opposite edges of said back section, each of said slides having a lug positioned near one extremity 135 thereof, a pair of bars each of which is movable transversely into and out of the path of travel of one of said lugs, means to actuate said bars, and means on said bars to prevent withdrawal of said actuating means while either of said bars is 140 positioned out of the path of travel of said lug.

7. In a loose leaf binder, a pintle slide, a bar operable to lock said pintle slide in closed position, means for actuating said bar, said means having two cam surfaces, a lug on said bar actuated by one of said cam surfaces to move said bar into unlocked position, and another lug on said bar actuated by the other cam surface to move said bar into locking position, said last-mentioned lug being adapted to prevent with- 145

- drawal of said actuating means while said bar is in unlocked position.
8. In a loose leaf binder, a pair of pintle slides, a locking mechanism including a pair of bars movable into and out of locking engagement with said slides, a pair of lugs on each of said bars, and actuating means for moving said bars, said actuating means including an individual cam for each of said lugs.
- 5 9. In a loose leaf binder, a pair of pintle slides, a pair of bars movable into and out of locking engagement with said slides, a detent normally holding said bars in locking position and means adapted to move said detent out of holding position, said means being further adapted to move said bars out of locking position.
10. In a loose leaf binder, a pintle slide, a bar movable into and out of locking engagement with said slide, a spring-pressed member normally holding said bar in locking position, means adapted to move said spring-pressed member to inoperative position, and means to prevent accidental release of said spring-pressed member from said inoperative position.
